UNITED STATES PATENT OFFICE

MILTON W. STERN, OF NEW YORK, N. Y., ASSIGNOR TO STERN & STERN, INC., OF NEW YORK, N. Y., A CORPORATION OF NEW YORK

DESIGN FOR A CLUSTER FOR RING OR PENDANT

Application filed June 28, 1932. Serial No. 44,208. Term of patent 7 years.

To all whom it may concern:

Be it known that I, MILTON W. STERN, a citizen of the United States, residing at New York city, borough of Manhattan, in the county and State of New York, have invented a new, original, and ornamental Design for a Cluster for Ring or Pendant, of which the following is a specification, reference being had to the accompanying drawing, forming part thereof.

Figure 1 is a plan view of the cluster, showing my new design, and

Figure 2 is a side elevation thereof.

I claim:

The ornamental design for a cluster for ring or pendant, as shown.

MILTON W. STERN.
